UNITED STATES PATENT OFFICE.

HENRY G. THOMPSON AND SAMUEL E. MOWER, OF MILFORD, CONNECTICUT.

LASTING-MACHINE.

SPECIFICATION forming part of Letters Patent No. 251,487, dated December 27, 1881.

Application filed August 5, 1881. (No model.)

To all whom it may concern:

Be it known that we, HENRY G. THOMPSON and SAMUEL E. MOWER, of Milford, New Haven county, State of Connecticut, have invented 5 an Improvement in Lasting-Machines, of which the following description, in connection with the accompanying drawings, is a specification.

This invention in lasting-machines is an improvement on the machine represented in 10 United States Patents Nos. 193,446, 208,127, and 212,824, to which reference may be had, the object of the present invention being to improve the construction of some of the parts and add to the machine novel devices, whereby 15 better results may be obtained and the operation of the parts and their adjustment for work with different-sized lasts be improved.

In our present machine we have slotted the shanks of the toe and heel pullers or jaws, and 20 operated them by a pin carried by the tipping plate. We have provided the tipping plate with a screw, whereby it may be adjusted horizontally to bring the fulcrum of the said pullers in line with the center of the last. We 25 have placed the shanks of the ball and shank pullers in sleeves, and surrounded them by adjustable spiral springs, and have pivoted the forward parts of the ball-pullers so as to turn toward the toe of the last, when subjected to 30 strain, to take up the slack in the upper at the shank of the shoe. We have made the shank and ball pullers simultaneously adjustable by means of a right-and-left-hand screw, and have 35 made the said ball and shank pullers vertically adjustable, and have adapted them to be closed and opened by a rack-bar and pinion. The head carrying the working parts is pivoted so as to both tip and rotate. The extent to which the head may tip is controlled by adjusting-screws, 40 and the head has co-operating with it a locking device to hold it in upright or horizontal position.

Figure 1 represents, in side elevation and partial section, the main part of a lasting-machine containing our improvements; Fig. 2, a 45 partial section thereof on the dotted line *x x*. Fig. 3 is a top view of Fig. 1; Fig. 4, an end view of our improved machine, the base being broken out to show part of the head-locking device, the other portions not therein shown 50 being delineated at the lower part of Fig. 1;

Figs. 5 and 6, details of the toe-rest; Fig. 7, a sectional detail, showing one of the shank-pullers and means for operating the same, one of the levers carrying one of the pair of shank-pullers being broken away; Fig. 8, a partial side elevation of one of the shank-pullers detached; Fig. 9, a side elevation and a top view, partially in section, of one of the ball-pullers; Fig. 10, a detail showing the carriage which carries the support for the tipping plate at the heel of the last, screw to adjust it, the slide for the shank-pullers, and the right-and-left-hand screw for moving it and the carriage for the ball-pullers; and Figs. 11 and 12 are details 65 of one of the tipping plates and pullers to operate upon and lay the upper over upon the heel or toe of the last.

The head A, which contains the moving parts of the machine, is supported by a pivot or pin, 70 2, held by cheeks 3, rising from a rotating collared sleeve, 4, the shank of which, inserted into the base B and grooved, as at 5, Fig. 1, receives a screw, 6, that permits the sleeve to rotate in and prevents it being lifted from the 75 said base. The cheeks 3 carry a stop, 8, (shown as a screw,) and the lower part of the head A has two adjusting-screws, 9 10, the ends of which may be made to strike against the stop 8. These screws may be adjusted out or in to any 80 desired position, and enable the head A to be tipped more or less from a horizontal position, it turning on the pivot 2, to hold the head A in a horizontal position as long as may be desired. Its lower end is provided with an opening to receive the end of a locking device or 85 bolt, 12, extended through a spiral spring, 13, and down into the hollow base B, where it is connected by a suitable link with a foot-treadle, 14, the bolt being withdrawn, when it is desired to tip the head, by depressing the said 90 treadle. The upper part of this head A is grooved, as shown in Figs. 5 and 7, to receive the different carriages which support the lasting devices.

The toe and heel pullers or closing jaws or slides C C' at their forward ends are made as in United States Patent No. 212,824; but their shanks are provided with inclined slots *a a'*, each pair of slots receiving a pin, *b* or *b'*, fixed 100 on one of the tipping plates, *d* or *d'*, pivoted at or near their front ends on a horizontally-

movable plate-adjusting screw, *e* or *e'*, having a milled head by which to turn it. Each of these adjusting-screws is fitted into the screw-threaded upper ends of upright rods *f* or *f'*, 5 extended down through sleeves *g* or *g'*, each rod being provided with rack-teeth, as shown in Fig. 1. The screws *e* may be turned to adjust the tipping plate *d* laterally to the right or left, to keep the center pivot of the pullers *C* always 10 at the proper position with relation to a longitudinal central line drawn through the last from heel to toe. The pivot *h* of the pullers *C* rises from a sliding block, *i*, grooved at its sides, (see Fig. 11,) and fitted into a slot at the front 15 end of the tipping plate *d*.

The blocks and pullers or jaws thereon are moved backward and forward with relation to the tipping plate *d* by a hand-lever, *j*, having a link, *k*, joined by a suitable screw with the 20 said carriage, as in Fig. 12, the pullers *C*, as they are moved forward, being gradually closed as their slotted shanks are drawn forward over the stationary pin *b*. Slitting the shanks of the pullers enables us to dispense with the links 25 shown in United States Patent No. 193,446, and making the slots in the shanks of the jaws is a better and cheaper construction than slotting the plate, and then providing each shank with a pin to enter such slots, as in United States 30 Patent No. 193,445.

The tipping plate *d* is provided with a segmental bar, *l*, having ratchet-teeth, (see Figs. 3 and 4,) engaged by a pawl, *m*, pivoted upon the hand-lever *j*, a link, *n*, and elbow-lever *o*, also 35 pivoted upon the said handle, being employed to operate the said pawl to remove it from the ratchet-teeth when the puller or jaw *C* is to be retracted, a suitable spring, *p*, so holding the pawl *m* as to engage the ratchet-teeth of the 40 said bar *l* as the puller *C* is being moved forward, thus preventing the return of the lever *j* until desired.

The lever *o* and pawl *m* may be moved by closing the hand on the handle of the hand-lever *j*.

The tipping plate *d* may be tipped by the screw *r*, fitted into the end of the rigid arm *s*, attached to the upper end of rod *f*, to enable the pullers or jaws *C* to be placed in proper position with relation to the spring or curvature of the toe or heel of the last *D* at its bottom. The rack of the rod *f* is engaged by a sector, *t*, on a short shaft, 40, (see Fig. 2,) provided with a hand-lever, *u*, having a pawl, *v*, engaging 55 a ratchet-bar, much as in United States Patent No. 208,127.

The sleeve *g* is mounted on a carriage, *G*, (see Figs. 1 and 4,) and is made horizontally adjustable by a screw, *H*, having a suitable 60 thumb-nut attached to it, the said screw being so held by a cross-piece of the head *A* that it cannot be moved horizontally as it is rotated.

The devices for moving the toe and heel pullers and adjusting them and their carriages 65 are substantially alike, and we have marked the devices connected operatively with heel-

pullers *C'* with the same letters used to designate like parts in connection with the toe pullers or jaws *C*, adding, however, to said letters the prime-mark. Thus *b* and *b'* are like devices. 70

The shank and ball pullers, which engage the upper along the shank and ball of the last, and their operative devices, are substantially alike; so in describing them we shall use for one set second powers of certain letters, and for the 75 other the third powers of the same letters.

The toe-rest *I* has its shank *J* (see Figs. 1 and 5) fitted to slide vertically in grooves of the upright part of the carriage *a'* and made vertically adjustable therein by an adjusting device, 80 15, (shown as a screw.)

The last-holding heel-pin, (shown in dotted lines, Fig. 1,) entered into the last *D*, forms part of an internally-threaded sleeve, 16, fitted to the upper end, 17, of a right-and-left-hand adjusting-screw, 17 19, provided with a collar, 18, the lower end of the said adjusting-screw being entered into a longitudinally-adjustable block, 20, below the under side of the longitudinally-movable carriage *a'*. The carriages 90 *a* and *a'* are bored longitudinally and threaded to receive the right and left threads of the long screw *M*, having the thumb-nut 22, the said screw being employed to simultaneously adjust in opposite directions the said carriages *a* *a'*, 95 carrying the toe-rest and heel-pin. The screw *M* is fitted loosely to the carriages *G* *G'*, as shown in Fig. 10 by the carriage *G'*.

The shank-puller is composed of a shank, *b'*, having a shoulder to receive against it one end 100 of a spiral spring, *c'*, the shank having at its front end the pivoted jaw *i'*, provided with teeth *j'* and the presser-foot *k*, substantially as in United States Patent No. 208,127. The shank *b'* is extended through a sleeve, *d'*, secured in 105 the hollow head *f'* of a swiveling and adjustable pin, *g'*. A sleeve-nut, *e'*, inserted in the sleeve *d'* against one end of a spring, *c'*, keeps the shank-puller pressed outward with more or less force, the said shank entering the sleeve *d'* 110 and compressing the spring *c'* when the strain exerted by the shank-puller on the material in the shank of the shoe is too great. The stems *g'* enter split sockets at the upper ends of carrying-arms *l'* *m'*, and are adjustably held there-in by the screws *h'*. The arms *l'* *m'* are pivoted at their lower ends upon arms of a vertically-adjustable slide, *n'*, having a dovetailed projection, *o'*, (see Fig. 1,) fitted into a dovetailed recess in the vertical portion *p'* of the 115 carriage *a'*, the said slide and connected arms and shank-pullers being vertically adjustable by means of the elbow-lever *r'*, one arm of which (see Figs. 1 and 7) is extended under the said slide and a screw, *s'*, carried by the 120 other end of the said elbow-lever, the end of the said screw bearing against the edge of the upright *p'*. The arms *l'* *m'* are joined operatively, so as to be moved simultaneously 125 toward and from the center of the last by means of a bar, *t'*, pivoted at one end to the lever *m'*, and provided at its under side, near its other

130

end, with rack-teeth to be engaged by a sector, u^2 , on a suitable shaft, v^2 , having a hand-lever, w^2 , secured to it, the teeth of the bar t^2 being kept down in engagement with the sector by a spring, 25. This hand-lever has a pawl, A^2 , (see Fig. 7,) connected by rod B^2 with the elbow-lever C^2 , operated by a spring, E^2 , the said lever C^2 and spring enabling the pawl A^2 to be lifted from engagement with or 5 permit it to engage a ratchet-toothed sector, like that marked 26 in Fig. 4, that sector, however, being the one with which the like pawl, A^3 , of the hand-lever w^2 of the ball-puller portion engages. As the hand-lever w^2 or w^3 is turned 10 to move the sector like u^2 , one for each hand-lever, the said pawls A^2 or B^2 , in engagement with a ratchet like that marked 26, will retain the hand-levers and arms of the shank and ball pullers in the positions to which they have 15 been brought by the said hand-levers.

The ball-pullers, which engage the material of the shoe in advance of the shank-pullers, (shown in Figs. 3, 7, and 8,) have been constructed to move somewhat toward the toe of 20 the last, to thus take up the slack in the material in the shank of the upper. To accomplish this novel result the heel-pullers (shown separately in Fig. 9) have their toothed portions i^3 j^3 and presser k^3 attached to a block, 28, 25 mounted to turn a little horizontally on a vertical pivot, 29, inserted into the forked forward end of the shank b^3 , the said shank being recessed to receive a screw, 30, the normal position of which is to keep the head 28 pressed 30 out, as in Figs. 4 and 9. The forked forward end of the shank b^3 also serves as a guide for the laterally - swinging toothed puller and presser i^3 j^3 .

The slide n^3 , which carries the arms l^3 m^3 (see Fig. 4) for the ball-pullers, is adapted 40 to be adjusted vertically on the upright part p^3 of the carriage a^2 , which also carries the toe-rest, by means of the screw s^3 , carried by a lever like that marked r^2 , it operating as does 45 the lever r^2 .

The pawl-and-ratchet contrivance, in connection with the hand-lever for operating the toe-pullers C , enables the latter to be held in the position at which they are left by the said 50 hand-lever..

Rotating and tipping the head enables the operator, in lasting a shoe, to bring the same in front of him in just the desired position both when pulling over the upper and tacking 55 or nailing it in place upon the usual inner sole on the last.

We claim—

1. In a lasting-machine, the horizontally-rotating collar and head pivoted thereon, provided with the toe and heel pullers or jaws, combined with the stationary base, the adjusting devices to regulate the inclination of the head when tipped, and locking device to hold the head in horizontal position, substantially 60 as described.

2. The head A and rotating collar upon

which it is pivoted and the stationary base B, combined with the bolt or locking device 12, to engage and hold the head, substantially as described.

3. The toe and heel pullers, head A, to carry them, the horizontally-rotating collar upon which the head is pivoted, the base, and the bolt or locking device 12, to engage and hold the head, combined with adjusting screws or devices to regulate the inclination of the head when tipped, substantially as described. 70

4. The carriages a^2 a^3 , the toothed shank-puller, and the ball-puller pivoted upon its shank-piece that it may move forward, as described, combined with a right-and-left-hand screw, to simultaneously adjust the said carriages toward or from each other, substantially as described. 80

5. The horizontally-movable carriage a^2 , its upright guiding portion, the ball-pullers, their supporting mechanism, and vertically-adjustable toe-rest, combined with the toe pullers or jaws, to operate substantially as described. 85

6. The toothed shank-pullers, their carrying-arms, and slide on which the said arms are pivoted, combined with the rack-bar, toothed sector, and lever to move it and operate the rack-bar to close the shank-pullers, substantially as described. 90

7. The toothed shank-pullers and pressers, their carrying-arms pivoted upon the slide n^2 , and the toothed rack and sector to operate the said arms, combined with a lever to operate the sector, a pawl carried by the lever, and a ratchet-plate the teeth of which are engaged by the said pawl, substantially as described. 95

8. The toothed shank-puller and the presser pivoted upon the shank-piece b^2 , the sleeve d^2 , tubular nut, and spring, combined with the holder f^2 , substantially as described. 100

9. The holder f^2 , provided with a stem, g^2 , the lever l^2 , bored and split to receive the said stem, the sleeve d^2 , and tubular nut and spring, combined with the shank b^2 , pivoted to the pullers and pressers thereon, substantially as described. 110

10. The pivoted and toothed ball-puller and its presser-foot attached to a block arranged to turn on a vertical pivot connecting the said block and the forward end of the shank b^3 of the said pullers, combined with spring 30, to enable the ball-pullers, when straining the upper to the last, to move forward toward the toe of the last to take up slack material in the shank, substantially as described. 115

11. The toothed shank or ball pullers provided with pressers, the puller-arms and slides upon which they are pivoted, and carriages to support the said slides, combined with an elbow-lever and adjusting-screw to determine the vertical position of the slide and pullers, and with a rack-bar and toothed gear to operate the arms which carry the pullers, substantially as described. 125

12. The sliding carriage and the pivoted pullers or jaws C, having their crossed shanks pro- 130

vided with independent slots, as described, at the rear of the pivot holding the said jaws, combined with a stationary pin to enter the slots of the said crossed shanks and close or 5 open the pullers or jaws as the pullers or jaws are reciprocated, substantially as described.

13. The toe pullers or jaws C, the carriage or block on which they are pivoted, and the hand-lever and intermediate devices to move 10 the said block or carriage, combined with an independent pawl and ratchet to retain the said pullers or jaws forward and prevent them being moved backward until the pawl and ratchet are released, substantially as described.

15 14. In a lasting-machine, toe and heel pullers or jaws, tipping plates upon which they are adapted to slide, screws to adjust the tipping

plates at their rear ends, and a screw to adjust each tipping plate and jaws laterally to center the pullers or jaws with relation to the last, 20 combined with shank-pullers mounted on arms pivoted upon a vertically-movable slide and with a toothed bar and gear to actuate the said arms and pullers in unison, substantially as described. 25

In testimony whereof we have signed our names to this specification in the presence of two subscribing witnesses.
